COMBINATION HEMOSTAT AND INTRAVENOUS NEEDLE

Robert J. Militana, 87 NE. 88th St., Miami, Fla.
Filed July 15, 1960, Ser. No. 43,184
4 Claims. (Cl. 128—322)

This invention relates generally to surgical instruments and is more particularly directed to such an instrument which automatically positions an intravenous needle in a vein or artery.

In general this invention consists of a scissor type clamp such as a hemostat upon which is mounted a holder for a hypodermic needle, which holder operates in unison with the hemostat so that when the jaws of the hemostat have engaged the walls of the vein to block off the flow of blood therethrough, the hypodermic needle is simultaneously and automatically thrust forwardly into the vein to permit the flow of intravenous therein. When the hemostat is manipulated to release the vein of the jaws of the hemostat the hypodermic needle is quickly and gently withdrawn from its position in the vein.

Therefore it is a principal object of the present invention to provide a surgical instrument which permits a hypodermic or intravenous needle to be easily and properly inserted into a vein, artery and the like.

Another object of the present invention is to provide a scissor-type clamp such as a hemostat with a toggle joint support for an intravenous needle operatively connected thereto, whereby upon the clamping of a vein or artery, the support thrusts the needle forwardly into the vein or artery beyond the position at which the vein is clamped by the instrument.

Another object of the present invention is to provide a scissor-type clamp such as a hemostat with a holder for an intravenous needle mounted thereon whereby the device need not be surgically sterile since the manner of receiving the intravenous needle is such that the needle which must be surgically sterile is not caused to become unsterile.

A still further object of the present invention is to provide a scissor-type surgical clamp with a holder for intravenous needles, which device will receive needles of various sizes in length and cross section.

With these and other objects in view, the invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

FIGURE 1 is a perspective view of an intravenous surgical clamp embodying my invention with a vein illustrated by dotted lines.

FIGURE 2 is a similar view showing the manner of operation of the device with the hemostat in a closed position.

FIGURES 3 and 4 are detailed cross-sectional views taken along the lines 3—3 and 4—4 respectively, of FIG. 1.

FIGURE 5 is a cross sectional view taken along the line 5—5 of FIGURE 3.

FIGURE 6 is a fragmentary perspective view of another construction of the hypodermic needle holder capable of receiving needles of various sizes.

FIGURE 7 is a cross sectional view taken along the line 7—7 of FIGURE 6.

2

FIGURE 8 is a cross sectional view similar to FIGURE 7 showing a still another construction of the hypodermic needle holder.

FIGURE 9 is a fragmentary perspective view of an intestinal clamp embodying my invention.

Referring to the drawing wherein like numerals are used to designate similar parts throughout the several views, the numeral 10 refers generally to my surgical instrument consisting of a scissor-type clamp commonly known as a hemostat or intravenous clamp having a pair of handle members 11 and 12 with finger receiving members 13 and 14 at one end and opposed facing jaws 15 and 16 at the other end. The handle members 11 and 12 are pivoted together adjacent their jaws 15 and 16 by

10 a pivot pin 17, the handle member 11 being slotted as at 18 to form bifurcated members 19 for receiving a leg member 20 of the handle 12 therebeneath. Secured to the top of the pivot pin 17 is a sleeve 21 for receiving tele- 15 scopically the body portion of a hypodermic needle 22.

20 Adjacent the finger engaging members 13 and 14 at their inner portions are a pair of opposed clamp members 24 and 25 which are adapted to become interengaged to lock the jaws 15 and 16 in a closed position. This occurs when the handle members 11 and 12 have been pivoted 25 about the pivot pin 17 in the direction toward each other.

Carried by the handle members 11 and 12 are a pair of 30 toggle arms 26 and 27 whose inner ends are pivoted together by the pivot pin 28 and their outer ends pivoted by pivot pins 29 and 30 to the handle members 11 and 12 respectively. On the top portion of the pivot pin 28, there is mounted an open ended bracket 31 provided with a cap 32 pivoted at one side as at 33 for retaining therein the base member 34 of the hypodermic needle 22. The base member 34 which is tapered at both its ends is pre- 35 vented from sliding within the bracket 32 by the ends of the bracket which taper likewise and engage the base member 34 at both ends. Attached to the base member 34 is a rubber hose 35 which conducts the flow of blood, plasma, medicinal fluids, etc. from a bottle to the needle 22 and into a vein or artery 36, the latter being indicated by dotted line.

In the normal operation of the surgical instrument 10, a person will take the device 10 by the finger engaging members 13 and 14 with one hand and the hypodermic needle 22 at its base portion 34 to which the hose 35 had been attached, all of which had been previously sterilized. The operator will insert the needle 22 through the sleeve 21 and slide it therethrough until the base member 34 can be slipped into the bracket 31 and the cap 32 swung to its closed position. Now the handle members 11 and 12 are made to swing in a direction away from each other pivoting about the pivot pin 17 to cause the jaws 15 and 16 to arrive at an open position. Simultaneously with the handle members 11 and 12 moving away from each other, the toggle members 26 and 27 will pivot about the pivot pin 28 and swing from a side-by-side folded position to an open and almost aligned position as shown by FIGURE 1. The swinging movement of the toggle members 26 and 27 causes the needle 15 to slide in the sleeve 21 away from ends of the jaw members 15 and 16. Now, the operator will place the jaws 15 and 16 astride the vein or artery 36 with the end of the needle in close proximity to the artery 36. Force is applied by the operator's fingers on the finger pieces 13 and 14 to cause the handle members 11 and 12 to pivot about the pivot pin 17 in a direction towards each other.

This causes the jaws 15 and 16 to come toward a closed position, whereby the side walls of the artery 36 are engaged and squeezed together. Simultaneously therewith, the toggle members 26 and 27 pivoting about their pivot pins 28, 29 and 30 will swing toward each other and cause the inner ends of the toggle members 26 and 27

as well as the pivot pin 28 and bracket 31 to slide in a direction toward the sleeve 21. The base member 31 as well as the hypodermic needle 22 is made to slide forwardly to cause the free end of the needle 22 to slide in the direction of the artery 36 which is now being gripped by the jaws 15 and 16. The hypodermic needle 22 slides sufficiently to cause the end of the needle 22 to pierce the upper wall of the artery 36 and move inwardly thereof, a relatively short distance. The clamps 24 and 25 now engage each other to hold the device 10 closed. The device 10 is now in position to permit the intravenous medicinal fluids to flow into the artery 36 while the flow of blood in the artery is stopped by the tight gripping action of the jaws 15 and 16.

When the operator has decided to stop the intravenous flow of fluid into the artery 36, he again grasps the finger pieces 13 and 14, presses them together slightly to release the clamps 24 and 25 and then forces the finger pieces 13 and 14 in a direction away from each other.

This causes the jaws 15 and 16 to swing to an open position and release their hold on the artery 36. At the same time, the toggle members 26 and 27 pivot on the pivot pins 29 and 30 to swing the inner ends of the toggle members 26 and 27 which support the bracket 31 and the needle base member 34 in a direction away from the sleeve 21. This effects the withdrawal of the hypodermic needle 22 from the artery 36, the instrument 10 now being ready to be used again after being cleaned and sterilized.

In order to increase the versatility of the surgical instrument 10 so that hypodermic needles 22 of various sizes may be accommodated by the device 10, there is shown a modified structure of the needle receiving sleeve 21. In FIGURES 6 and 7 there is shown a cradle 40 having resilient leg portions 41 which are arcuate in shape having outwardly extending lip portions 42 for receiving a needle 21. The remaining structure of the hemostat 10 is identical to that described hereinabove. Instead of sliding a needle within the rigid sleeve 21 as must be done in the instrument 10 previously described, the hypodermic needle 43 is laid on the lips 42, 42 and forced downwardly, the leg portions 41 being resilient will flex outwardly and permit the needle 43 to slip into position. The flexible leg portions 43 will bear slightly on the side wall of the needle 43 yet will permit different sized diameter needles to be accommodated by and slide within the cradle 40 when the hemostat 10 is actuated as afore-said.

Referring now to FIGURE 8 there is shown a holder 121 for the hypodermic needle 22 in lieu of the holder 21 previously described, which holder 121 is removable so that holders 121 of different sizes may be used as various sizes of needles are applied to the instrument 10. The remaining structure of the instrument 50 is identical in construction with that of the above described surgical instrument 10. The leg members 19, 20 of the hemostat 10 are pivotally secured by a pivot pin 117 whose upper end is split or bifurcated as at 120 with a peripheral shoulder 118 formed at substantially its mid-portion which in co-operation with a nut 122 threaded on the end of the pivot pin 117 secures the members 19 and 20 together for pivotal movement. The needle holder 121 is provided with a sleeve portion 123 whose inner diameter permits the use of an appropriately sized hypodermic needle 22. Depending from the lower surface of the sleeve 123 is a socket 119 which fits tightly and firmly over the bifurcated end 120 of the pivot pin 117. The socket 119 which frictionally engages the bifurcated end 120 can be removed from the pin 117 upon application of an upward force on the sleeve 123 whereby the hypodermic needle holder 121 becomes disengaged from the pin 117. If a different sized hypodermic needle 22 is needed, a needle holder 121 having a sleeve portion 123 that will properly accommodate the body portion 22 of the desired

hypodermic needle is selected and forced in place on the bifurcated end 120 of the pivot pin 117.

In FIGURE 9 there is shown another adaptation of my invention to a conventional surface intravenous clamp 50 having handle portions 53, 54 and jaw portions 51 and 52 terminating in flat ring portions 55, 55. The clamp 50 is provided with a pivot means as described hereinabove and a hypodermic needle holder 21 mounted thereon. In this instrument 50 any of the holders 40, 121 may be used in lieu of the holder 21 though the latter is shown in position in order to explain the operation of the surgical instrument 50. In the normal use of the surface intravenous clamp 50, the operator grasps the vein to be fed intravenously by the flat rings 55 and causes the jaws 51 and 52 to come to a closed position. As is explained above in connection with the instruments 10, the handles 53, 54 are locked together. Now the operator takes the hypodermic needle 22 and slides it through the holder 21, or whatever other holder might be used, and directs the point of the needle 22 at the vein that is being held by the rings 55. A further forward movement of the needle 22 will cause the vein to be pierced and the needle 22 to be in position to permit the flow of intravenous fluids through the needle and into the vein. In this surgical clamp 50, the piercing of the vein by the needle 22 is not done automatically as occurs in the intravenous clamps 10 as described hereinabove. After the vein is grasped by the clamp 50, the operator can use the sleeve 21 for guidance in sliding the needle toward the vein. The sleeve 21 as well as the instrument 50 operates thereafter as a holder for the needle 22.

What I claim as new and desire to secure by Letters Patent of the United States is:

1. A surgical instrument comprising a pair of handle members with jaw members formed integrally with said handle members, pivot means pivotally mounting said handle means and said jaw members, needle guide means mounted in proximity of said pivot means, toggle means pivotally secured to said handle members, needle support means mounted on said toggle means and a hypodermic needle slidably mounted on said needle guide means and extending between said handle members and supported on said needle support means whereby upon the swinging of said jaw members and said handle members to a closed position said toggle means will cause said needle to slide in said needle guide in the direction toward the free ends of said jaw members.

2. A surgical instrument comprising a pair of handle members with jaw members formed integrally with said handle members, pivot means pivotally mounting said handle members and said jaw members, sleeve means mounted on said pivot means, a pair of toggle members, second pivot means securing one end of said toggle members together, further pivot means pivotally securing the other end of said toggle members to said handle members, a needle support bracket mounted on said second toggle pivot means and a hypodermic needle having a body portion and a base portion, said body portion being slidably mounted in said sleeve means and said base portion removably mounted in said support bracket whereby upon the swinging of said handle members and said jaw members to a closed position said hypodermic needle will slide in said sleeve means in the direction toward said jaw members.

3. A surgical instrument comprising a pair of handle members with jaw members formed integrally with said handle members, pivot means pivotally mounting said handle members and said jaw members, a cradle mounted on said pivot means, a pair of toggle members, second pivot means securing one end of said toggle members together, further pivot means pivotally securing the other end of said toggle members to said handle members, a needle support bracket mounted on said second toggle pivot means and a hypodermic needle having a body portion and a base portion, said body portion being slide-

bly mounted in said cradle and said base portion removably mounted in said support bracket whereby upon the swinging of said handle members and said jaw members to a closed position said hypodermic needle will slide in said cradle in the direction toward said jaw members.

4. A surgical instrument comprising a pair of handle members with jaw members formed integrally with said handle members, pivot means pivotally mounting said handle members and said jaw members, needle receiving means removably mounted on said pivot means, a pair of toggle members, second pivot means securing one end of said toggle members together, further pivot means pivotally securing the other end of said toggle members to said handle members, a needle support bracket mounted on said second toggle pivot means and a hypodermic needle

15

having a body portion and a base portion, said body portion being slidably mounted in said removable needle receiving means and said base portion removably mounted in said support bracket whereby upon the swinging of said handle members and said jaw members to a closed position said hypodermic needle will slide in said needle receiving means in the direction toward said jaw members.
